UNITED STATES PATENT OFFICE.

THOMAS L. LAWTON, OF PHILADELPHIA, PENNSYLVANIA, ASSIGNOR TO LOUIS D. ERBEN.

DESIGN FOR A CURTAIN, &c.

SPECIFICATION forming part of Design No. 22,435, dated May 16, 1893.

Application filed April 3, 1893. Serial No. 468,955. Term of patent 3½ years.

To all whom it may concern:

Be it known that I, THOMAS L. LAWTON, of the city of Philadelphia, county of Philadelphia, State of Pennsylvania, have invented and produced a new and original Design for Covers and Curtains, of which the following is a specification.

The nature of my design is fully represented in the accompanying india ink drawing, to which reference is made.

I claim—
The design for covers and curtains as herein shown and described.

THOMAS L. LAWTON.

Witnesses:

JAMES S. BROWN,
JOSEPH L. DAVIDSON.
